UNITED STATES PATENT OFFICE.

WALTER COURTLAND LOONEY, OF DANVILLE, KENTUCKY.

DEVICE FOR AUTOMATICALLY ELEVATING THE ASSEMBLERS OF TYPOGRAPHICAL MACHINES.

Application filed July 13, 1921. Serial No. 484,489.

To all whom it may concern:

Be it known that I, WALTER COURTLAND LOONEY, a citizen of the United States, residing at Danville, in the county of Boyle 5 and State of Kentucky, have invented a new and useful Device for Automatically Elevating the Assemblers of Typographical Machines, of which the following is a specification.

10 The object of my invention is to provide a device adapted to automatically elevate the assembler of a linotype or similar typesetting machine a distance of about $4\frac{1}{2}$ inches and bring it back to first position instead of 15 manipulating the assembler by the customary crank at the right hand corner of the keyboard. It is also my object to provide the novel combination and arrangement of parts hereinafter described and illustrated 20 in the accompanying drawings, in which—

Figure 1 is a side elevation of the invention with the linotype machine shown in diagram;

Fig. 2 is a front view of the attachment, 25 in normal position;

Fig. 3 is a vertical section with the clutch engaged;

Fig. 4 is a view showing the device as it descends, with roller 4 riding on the face of 30 small cam 45 and the right and left-hand latches almost in the act of recatching;

Fig. 5 is a top plan of the machine;

Fig. 6 is a vertical section, partly in elevation, and with a dotted line view showing 35 the operation of the lifting arms and the cam action;

Fig. 7 is a vertical section looking in the opposite direction from the view shown in Fig. 6;

40 Fig. 8 is a horizontal section on line 8—8 of Fig. 2; and

Fig. 9 is an enlarged detail of members 31, 24, and 33.

Like numerals designate like parts in each 45 of the several views.

Referring to the accompanying drawings, I provide a base board 1 on which is mounted a suitable frame 7 in which is journaled the shaft 3 which carries the fly-wheel 4 50 which is spaced from the frame 2 by the spacing sleeve 5. I provide a clutch 6 affixed to the shaft 3 by the set-screw 7 so as to continuously rotate with shaft 3. I further provide a loosely mounted clutch 8 slidably

mounted on shaft 3 and adapted to mesh 55 with clutch 6. Clutch 8 is provided with the extended sleeve 9 as shown in Fig. 2. A cam 13 is affixed to sleeve 9 by the set-screw 12. I further provide a lifting cam 10 mounted on sleeve 9, and also a latch sleeve 11 mounted 60 on sleeve 9 adjacent cam 13. I further provide a pivoted trigger or latch 14 adapted to releasably engage latch sleeve 11. I provide a suitable rod 15 operatively connected with latch 14 and attached to the 65 counter-weight 16 to which the trip wire 18 is attached, as shown in Figs. 1 and 2, said trip wire in turn being attached to key lever 19, which is pivotally attached to the keyboard frame by pivot 20. Key lever 19 is 70 provided with a suitable key 21 positioned at the left of the linotype keyboard K, as shown in Fig. 1. I provide a suitable supporting strap 17 functioning as a guide member for the vertically disposed latch 75 lock 15.

Referring to Figs. 2 and 3 I provide suitable springs 22 positioned to bear against latch sleeve 11. Cam 10 is provided with an extension or arm 23, as shown in Fig. 2 80 and Fig. 6, said arm being pivotally attached to the lower end of the lower half of the connecting rod 24, the upper half 30 of which is bolted to rod 37 of the assembler. Member 30 is provided with an extension 31 85 which is slidably mounted in the socket 32 in the upper end of member 24, and which is in contact with the coiled spring 33 positioned in socket 32, as shown in Fig. 9.

Referring to Fig. 1, I provide a strap 25 90 attached to connecting rod 24 near the upper end. I further provide a suitable spring 27 having a hook 26 by which it is attached to strap 25, and having a hook 28 by which it is attached to a suitable hook or screw stand- 95 ard 29 secured to the baseboard 1. I provide a retaining hook 35 engaging eye 36 in strap 25, said hook 35 being in turn attached to a strap 34 secured to the lower end of the upper half 30 of the connecting rod. 100 The assembler 38 which is operated by the connecting rod is indicated diagrammatically in Fig. 1.

I provide a chain 39 which is secured to the lower end of cam arm 23, as shown in Fig. 6 and which is run over a suitable pulley 40 secured to the base-board 1. The end of chain 39 is attached to a spring 41, which

in turn is attached to the free end of weighted lever 42, which carries a weight 46 at its other end. Weighted lever 42 is affixed to member 44' which also carries the roller 44, 5 which contacts with cam 45, as shown in Fig. 4.

I provide a suitable indenture 62 on the face 59 of cam 10, as shown in Fig. 8 in contact with the upright rod 55 at the appropriate time to cause the clutches 6 and 8 to disconnect. The upright rod 55 is reinforced by suitable braces 58, as shown in Fig. 2, and 57 and 56, as shown in Fig. 5.

I provide a shaft 43 mounted in frame 2 and affixed to or mounted on hub portion 44' 15 of weighted rod 42. I also provide a latch sleeve 52 on shaft 43, said sleeve having an annular latch portion 61, releasably engageable with the latch 49 which is mounted on pivot 54 as shown in Fig. 2. I provide a suitable guide 53 mounted on the frame of the machine and functioning as a vertical guide for latch 49.

Referring to Fig. 7, I provide a suitable projection 47 affixed to the clutch 8 and adapted to contact with the cam arm 48 on latch 49. I provide a cam arm 48, to which is attached weight 50. Cam 10 is provided with the cam face 59, as shown. I provide a suitable stop 60, attached to base-board 1, against which the lower half 24 of the connecting rod rests when in its lowest and non-operating position.

The normal nonoperating position of the device is shown in Figs. 1 and 6. When the key 21 is pressed it operates key lever 19 and raises wire 18 and counterweight 16. As counterweight 16 is operatively connected to latch 14 by rod 15, the raising of the counterweight releases the latch 14 from its operative engagement with latch sleeve 11, thereby allowing the springs 22 to press latch sleeve 11 against cam 13 which is affixed to sleeve extension 9 of clutch member 8, thereby sliding the clutch into mesh with the corresponding clutch 6. The clutch 6 being keyed to shaft 3 is constantly in motion, whereas clutch 8 is normally at rest. The engagement of these clutches causes the rotation of cam 10 which is actuated by the small cam 13 which latter cam is secured to the sleeve extension 9 of clutch 8 by set screw 12, and rotates with said clutch. The arm 23 which is an extension of cam 10 is thus raised on the engagement of the clutches 8 and 6, thus raising the connecting rod sections 24 and 30, and the member 37 which operatively connects the connecting rod with the assembler 38, as shown in Fig. 60 1, and raises the latter automatically in the manner above described.

When the device is in non-rotating position both latch 14 and latch 49 are engaged with the respective latch sleeves 11 and 52. 65 When the arm 23 and the connecting rod

members 24 and 30 are at their highest point neither latch 14 nor latch 49 is engaged with the respective latch sleeves. The projection 47 on the right hand clutch (see Figs. 2 and 7) comes into contact with the arm 48 on the left hand latch 49 just before the main arm 23 of cam 10 reaches its highest point, which contact releases the left hand latch 49, allowing the spring 51 to push latch sleeve 52 and roller 44 against the small cam 13, as shown in Fig. 8. When the assembler 38 has been raised to the proper height it descends by its own weight, assisted by the long spring 27 which is suitably secured to the base-board 1 and to strap 35 attached to connecting rod member 24, as shown in Fig. 1. As roller 44 is in position against cam 13 consequently the roller rides on the face of the cam while the cam arm 23 is descending, which action causes both the right and left hand latches to again engage the respective latch sleeve.

The operation of roller 44 is controlled by the weighted lever 42 and by the spring 41 and the catch chain 39 which is mounted on pulley 40 and attached to the lower end of the connecting rod member 24 at one end, and at the other to the weighted lever 42. Roller 44 travels over the top of cam 10 (and cam 13) as the arm 23 is ascending, and is pulled into position by chain 39 so that it will ride on the face of the cam 45 as the arm 23 descends, thereby forcing both latch sleeves back to their original position and allowing the respective latches 14 and 49 to again engage the latch sleeve 11 and 52 respectively.

When the assembler has been raised by the device the upward movement of the main arm 23 brings the indenture 62 of cam 10 into contact with the perpendicular rod 55, thereupon causing the clutches to disconnect at the proper time and allow the assembler and the mechanism of the attachment operating the same to return by gravity to its original position, assisted by the spring 27. Both latches 14 and 49 are sufficiently weighted to prevent them from bouncing out of engagement with the latch sleeve when they fall into place.

I may provide any suitable means, such as shafts, belts and pulleys, for operatively connecting my attachment with the driving pulley of the linotype or other type-setting machine to which this device may be attached. The device will work satisfactorily on both the linotype and the intertype type-setting machines.

The right to attach a mechanical device to any part of the assembler of the linotype machine or to the rods connecting the assembler to the crank on the keyboard is hereby included among others in these specifications (provided the means of attachment used satisfactorily furthers said object of

automatically manipulating the assembler by mechanical means) is contemplated by my invention.

As the operator is not required to take one hand from the keyboard to raise the assembler for every new line of type, an important saving in time is effected, for the manipulation of a crank requires more time than the touching of the keys required for operating this device. In setting copy that is hard to read the operator is thus enabled to give more time to it, since with this attachment he can set type or manipulate the keys continuously without interruption to raise the assembler for each new line of copy.

The assembler is retained in elevated position until the transfer fingers slide the matrices therefrom by the conventional customarily employed on typographical machines of this type, whether my attachment is on the machine or not. The assembler is held in its elevated position only a fraction of a second as the transfer is made immediately.

What I claim is:

1. In a device for automatically elevating the assembler of a typographical or similar typesetting machine, the combination of a clutch operatively connected with the driving shaft of the linotype machine and continuously operated thereby, a second clutch normally disengaged from the first-named clutch, cam members loosely mounted on a shaft carrying the aforesaid clutches and arranged to throw the clutches out of operative engagement, spring controlled means for forcing the cam members into operative engagement to thereby set the clutches into operation, means operatively connected with one of the cam members and with the assembler of the linotype machine and operating to raise the assembler when the cam and clutch members are thrown into operation, and key operated means for releasing the above mentioned spring controlled means to throw the clutches into operative engagement.

2. In combination with the apparatus described in claim 1, means for automatically disengaging the clutch members when the assembler has been raised to its highest point by the above described mechanism.

3. In combination with the apparatus described in claim 1, means for automatically disengaging the clutch members when the assembler has been raised to its highest point

by the above described mechanism, and spring means for insuring a quick return of the assembler through its lowermost position after being raised by the above described apparatus.

4. In combination with the apparatus described in claim 1, a projection on the loosely mounted clutch, latch-means operated by said projection, a spring controlled sleeve releasably engaged by the aforesaid latch means, and a roller carried by said sleeve and positioned to contact with one of the cam members to cause the opposed latch member to recatch under predetermined conditions, and a weighted lever operatively connected with said sleeve and with the means for raising the assembler, for the purposes described.

5. In a device for elevating the assembler of a linotype or similar typesetting machine, the combination of assembler elevating means operatively connected with the assembler, said means including telescoping rods having a spring interposed between said rods, a cam member having an arm attached to the lower end of said assembler elevating means, a shaft having a fly wheel driven from the linotype machine, a clutch affixed to said shaft and rotating therewith continuously, a second loosely mounted clutch normally disengaged from the first mentioned clutch, key operated latch means normally holding the loosely mounted clutch in disengaged position, spring means for throwing the clutches into operative engagement when the key is operated and the aforesaid latch disengaged, means operated by the aforesaid cam for disengaging the clutches when the assembler has been raised to its highest position on operation of the key, and means for automatically re-setting the apparatus to its normal non-operating position after one operation of the assembler, substantially as and for the purposes described.

6. In a device for automatically raising the assembler of a typographical machine, cam operated weight controlled means for raising said assembler, manually operated means for setting said assembler elevating means into operation, means for throwing said means out of operation when the assembler reaches its highest position, and means for automatically re-setting all of the aforesaid mechanism to its original position.

WALTER COURTLAND LOONEY.
